UNITED STATES PATENT OFFICE.

FREDERICK WILLIAM RUDOLPH YAGER, OF CHICAGO, ILLINOIS.

MACHINE FOR MAKING METAL BINDING-STRIPS.

SPECIFICATION forming part of Letters Patent No. 696,784, dated April 1, 1902.

Application filed May 13, 1901. Serial No. 59,989. (No model.)

To all whom it may concern:

Be it known that I, FREDERICK WILLIAM RUDOLPH YAGER, a citizen of the United States of America, and a resident of Chicago, county of Cook, State of Illinois, have invented certain new and useful Improvements in Machinery for Making Metal Binding-Strips, of which the following is a specification.

10 Reference will be had to the accompanying drawings, in which—

Figure 1 is an end elevation of the machine. Fig. 2 is a view looking in the direction of the arrow 2 of Fig. 1. Fig. 3 is a vertical sectional view of the machine. Fig. 4 is a view looking in the direction of arrow 4, Fig. 3. Fig. 5 is a detailed sectional view of the parts which act upon the metal strip. Fig. 6 is a view similar to Fig. 5 with the parts in a different position. Figs. 7 and 8 are detailed views of parts that will be described later. Figs. 9 and 10 are detailed sectional views similar to Figs. 5 and 6 with the parts in a different position. Figs. 11, 12, and 13 are 25 details of parts that will be described later. Fig. 14 is a perspective view of a finished strip, the product of the machine.

The machine is designed to make the metal strip Y, such as is shown in Fig. 14, continuously and automatically from a flat sheet M of metal that is fed into the machine.

The strips are used for binding calendars and the edges of pictures or for any other analogous purpose.

35 The object of this machine is to produce the above-described metal strip in the simplest and most economical manner possible and by devices entirely automatic in all of the operations.

40 The invention consists of the devices and combinations set forth in the claims.

The machine is provided with any suitable frame F, to which there is fixed the table T. The table T is mounted at an incline sufficient 45 to cause the plate of metal M from which the strips are cut to slide down by force of gravity against the stops provided to catch it, thereby producing an automatic gravity feed of the metal plate M from which the strips are 50 cut. In place of the gravity feed an automatic positive feed may be introduced that will perform the same function. The plate

M slides down and is arrested by the stops S, Fig. 10, which are so adjusted as to allow the proper projection of the plate over the edge 55 of a shear-blade K, which is fixed to table T. A movable blade K', mounted in suitable guideways in the machine, coacts with the blade K and severs a strip from the sheet the width required, and a clamping-bar C clamps 60 the sheet during the cutting. The stops S and the shear-blade K' are connected to same actuating mechanism, and as the shear-blade descends the stops also descend, carrying with them the severed strip, until these stops S are 65 drawn below the surface of the platen P, which then receives the severed strip. The platen P is also on an incline sufficient to cause the severed strip to slide downward away from the shearing devices by gravity; 70 but to insure such sliding I provide fingers K², Fig. 5, which move suddenly outward at the proper instant and shoot the strips downward along the surface of the platen. Along the center of the surface of the platen P there 75 is provided a series of stops S², which catch the strip as it descends from the shear and arrest it momentarily until the completion of the bending and the ejection of the strip which preceded it, whereupon the stops S² are 80 automatically withdrawn, and the strip again descends by gravity against the stop G, Fig. 6, which arrests the strip in the proper position for bending, and when so arrested the clamping-blade B is actuated to clamp the 85 strip firmly against the lower edge of the platen P, and upon the completion of this clamping the stop G is lifted upward to position shown in Fig. 9, and the bender B' is actuated to rock over and bend the strip to 90 the desired form, after which the parts return to their normal position and the completed strip Y is discharged from them by gravity, as will be seen by Fig. 10.

The parts hereinbefore described may be of 95 any suitable form or construction adapted to perform the function of cutting and bending the strip, as described; but I prefer to use the forms shown.

The mechanism which actuates the several 100 parts may be of any suitable form or construction adapted to perform the function set forth; but I prefer to use the form herein shown.

The stops S are pivotally fixed to the bar S³, attached at the points S⁴ to the rods K³, which are connected to the eccentrics K⁴ on the cam-shaft D, which is the main driving-shaft of the machine and is driven by a pulley W through the medium of a clutch W', actuated by the rod W², connected to a rocker-shaft W⁴, provided with handles W⁵, which permits the operator to engage and disengage the driving power from either end of the machine.

The shear-blade K' is connected by the blocks K⁵ to rods K³, driven by the eccentrics K⁴, as described.

15 The clamping-bar C is fixed to blocks C', connected to the levers C², fixed on the shaft C³, and is actuated by the spring C⁴, mounted at the end of the machine, and the bar is withdrawn by means of the cam C⁵, connected to the shaft C³ through the medium of the cam-roller C⁶, arm C⁷, rod C⁸, and arm C⁹.

20 The kicker-fingers K² are mounted upon a bar R, which is pivoted at its ends in the frame of the machine and is actuated by a cam R' through the medium of a cam-roller R², arm R³, and rod R⁴, connected to the rod R by the lever R⁵. There is a spring upon the head of rod R⁴ to permit of the elastic connection of the rod R⁴ with the lever R⁵.

25 30 The stops S are made adjustable for different widths of strips by means of the details shown in Fig. 3 and Fig. 7. The stops S are mounted upon the bar S³ through the medium of studs S⁵ and springs S⁶, which permits the stops S to yield or rotate slightly about the bar S³ and the stops S to be sensitive to adjustment, as required, as follows:

Underneath stops S and extending across the frame of the machine is a bar E, which is 40 pivoted at its ends to the frame of the machine or to the platen P. The pivot-points are indicated by E'. Fixed to this bar E there is the lever E², which is adjusted by means of the thumb-screw E³ and spring E⁴, 45 causing the bar E to rotate about its pivots, and thereby raise or lower the stops S. The screw E³ is held by the block E⁵, fixed to the bar E⁶, fixed to the frame of the machine.

50 The stops S² are connected to a bar S⁷, Fig. 55, pivoted at its ends by the pivot-holes S⁸ to the under side of the platen P, and the bar S⁷ is actuated by means of the cam S⁹, connected to bar by means of the roller S¹⁰, arm S¹¹, rod S¹², and link S¹³. The cam serves to throw the bar S⁷ upward by means of the contact between the link S¹³ and the bar, while the weight of the bar causes the bar to descend when the cam permits it.

60 The clamping-blade B is mounted in pivots B⁹ at the ends of the machine and is actuated by the cam B³, connected to the shaft B⁹ through the medium of the roller B⁴, rod B⁵, and lever B⁶. The lever B⁶ is slotted to permit of an adjustment of the connection of the 65 rod B⁵ in order to exert more or less pressure in clamping the strip, as is required. The

clamp is released by the spring B⁷, connected to the arm B⁸, as shown in Fig. 1.

The stop G is composed of an angle-bar g, mounted upon bar G', pivoted at its ends to arms G², mounted on a shaft G³, which is actuated by cam G⁴ through the medium of the roller G⁵, arm G⁶, rod G⁷, and lever G⁸, and the spring G¹¹ returns the parts to their normal position. The bar G' is held in its position about its pivots by means of a lever G⁹, connected by the screw G¹⁰ to the shaft G³, the thumb-nut and spring on screw G¹⁰ permitting the required adjustment of the bar G' about its pivot to permit a close adjustment of the angle-bar g onto the bender B' when the cam is in position for that purpose.

75 80 Bender B' is mounted in pivots J at the end frames of the machine and is actuated by means of cams J', connected to pivots J through the medium of the roller J², arm J³, chain J⁴, and sprocket-wheels J⁵, fixed to the pivots J, and the bender is returned to its normal position by means of the springs J⁶.

85 Any suitable mechanism may be used to 90 perform the functions of actuating the parts, as hereinbefore described; but I prefer to use the mechanism shown.

What I claim is—

1. In a machine of the class described the combination of the shear for cutting the strips from a sheet, adjustable stops for determining the width of the strips to be cut, a discharging device for launching the strips forward after the cutting, an intermediate stop for arresting the travel of the strip edge bringing it into alignment, stops for adjusting the position of the strips to be bent with clamping and bending devices and means for automatically actuating the several parts, substantially as shown and described.

2. In a machine of the class described, the combination of a shear for cutting the strips, mechanism for discharging severed strip from the shear, stops for holding the severed strip in a position to be bent, and a clamping-bar and a revolving bender, substantially as shown and described.

3. In a machine of the class described, the combination with a feeding-table fixed at an angle insuring the sliding of a stock sheet placed thereon, of means for arresting the sliding at a certain point, shearing devices arranged to cut a strip from the lower side of the arrested sheet, an inclined platen in position to receive the severed strip, means for arresting the strip after it has advanced a certain distance upon the platen, and means for bending the strip.

4. The combination of a feeding-table, of a cutting-shear, adjustable stops for regulating the width of the strips to be cut, and a strip-launching device with stops and bending devices for bending the strips, substantially as shown and described.

5. In a machine of the class described, the combination with a feeding-table, of shearing

devices arranged to cut a strip from a sheet upon the table, stops normally limiting the advance of such sheet and at an adjustable distance from the shearing-line, a platen in position to receive the severed strip, means for clamping the strip against the platen, a rotary bender normally lying below one side of the strip when so clamped, and automatic means for rotating the bender toward the strip through approximately one hundred and eighty degrees, to bend the strip back upon itself.

6. In a machine of the class described, the combination with a feeding-table and shearing devices to cut a strip from a sheet thereon, a platen in position to receive the severed strip, strip clamping and bending devices, and stops between the severing and clamping devices to adjust and temporarily arrest the strip.

7. In a machine of the class described, the combination with a feeding-table and shearing devices for severing a strip from a sheet thereon, of stops adjustable in distance from the shearing-line, to vary the width of strips, a platen in position to receive the severed strip, an automatic stop to arrest the advancing strip when its side projects to the proper distance over the platen's edge, a clamping-plate to press the non-projecting portion of the strip against the platen, a bender normally alongside the place of the projecting portion of said strip, and means for swinging the bender about the edge of the clamping-plate to double the strip back upon itself.

8. The combination of a feeding-table, of adjustable stops for regulating the amount of feed, a cutting-off shear for severing the strip from a sheet as held upon the feeding-table, a platen for receiving the strip from the shear, and a bending device mounted

upon the platen for bending the strip after the cutting, said platen being recessed to permit the passage of the adjustable feeding-stops through the surface of the platen, substantially as shown and described.

9. In a machine of the class described, the combination with a feeding-table inclined at an angle insuring the sliding of a sheet placed thereon, of a similarly-inclined platen in position to receive a strip falling from the edge of the feeding-table, an automatic clamp for momentarily holding a sheet upon the feeding-table, automatic shearing devices for severing a strip while the sheet is so held, a clamp for holding a strip against the platen, and an automatic bender arranged to fold the strip back upon itself while thus clamped.

10. In a machine of the class described, the combination with a feeding-table and shearing devices near one side of the same, of stops adjustable in distance from the shearing-line, a platen slightly below, and parallel to, the strip at the instant of severing, a device for impelling the severed strip sidewise across the platen, and clamping and bending devices arranged to receive the strip and bend it.

11. The combination of a feeding-table, an adjustable stop for regulating the width of the feed, a shear for cutting a strip from the sheet as held upon the table, a launching device for discharging the strip from the shear, and a platen for receiving the strip from the shear and clamping and bending devices mounted upon the platen, substantially as shown and described.

Signed by me at Chicago, Illinois, this 7th day of May, 1901.
